KNEE EXERCISER

Harry J. Campbell, San Francisco, Calif.

Application December 19, 1934, Serial No. 758,212

3 Claims. (Cl. 128—25)

This invention relates to exercising apparatus in general, and has for its principal object an apparatus adapted for exercising the knee to overcome stiffness or inactivity thereof induced by 5 injury, disease, or as an aftermath of surgical work on or about the knee. Other objects of the invention are to provide such an apparatus which is portable and self-contained, and will provide for operation by the party whose knee is to be 10 exercised, also provide for stretching the leg with any desired degree of tension to bring the knee bones and muscles in correct position, also provide for a reading of the tension produced, also for adjusting the pivotal axis of the apparatus 15 coincident with, or above or below, the axis of the knee joint being exercised, all while the leg is under tension on the apparatus. Other objects and advantages of the invention will appear in the following description and accompanying drawing.

In the drawing Fig. 1 is a side elevation of the apparatus in place on a supporting table and with a man in place on the apparatus with right leg tensioned.

Fig. 2 is an end view of the apparatus as seen from the right-hand of Fig. 1 but without the man in place.

Fig. 3 is an enlarged view of the shoe showing the hook-attaching ring.

Fig. 4 shows an optional ankle strap.

Briefly described, the invention comprises a jointed frame, part of which rests on a table and is sat upon by the party using the device so that his weight holds it in place, and an outer or swinging section in which one of his legs is tensioned with the knee joint arranged substantially in line with the pivoted joint of the two parts of the frame, so that by swinging the outer part of the frame the knee may be exercised.

In the drawing 1 represents a common table, 2 the flat base-board-like portion of the frame resting on the table and to which the outer or swinging portion 3 of the frame is pivoted at 4 on a transverse axis extending substantially through the knee joint of a man 5 seated with one leg on the base board. The board portion may, of course, be secured to the table by any desired means or may consist of the top of the table itself, but the user's weight on a portable device as 50 shown has been found sufficient to hold the same in place to do all that is required of the apparatus.

The user is held in place and from sliding forward by a wide strap 6 passing over his hips and stomach and secured at the rear of the base 55 board by a suitable hinge 7. The base board is

wide enough to comfortably seat the thigh of the user and has a pair of side brackets 8 extending angularly upward and forward for bracing a pair of vertical guides 9 in each of which is a vertically slidable bearing block 10 which may be raised or lowered (about 3 inches each way) with respect to the knee joint by means of a vertical screw 11 threaded through the bearing blocks and manipulated by a small crank handle 12. Preferably a soft resilient pad 13, such as a flat rubber water bag filled with hot water, is positioned under the leg just above the knee at the forward rounded end of the base board.

The forward or swinging portion of the frame is made of two long side pieces 3 firmly joined at 15 their outer ends by a cross piece 14 which carries a loose pulley 15 at its inner side under which pulley passes a rope or chain 16 provided with a hook 17 for hooking to a ring 18 secured to the sole of the user's shoe 19, or to a strap 20 from an 20 ankle band 21 secured tightly about the ankle of a user's leg as indicated in Fig. 4 of the drawing.

The rope 16 extends from pulley 15 under a second pulley 21 secured at the outer end of the side member of the swinging frame and extends 25 along the frame and secures to a pulley block 22 over which block and a second pulley block 23 secured to the upper portion of the side member 3 a second rope 25 passes, and to the outer side of which member at a point adjacent pulley 30 block 23 is secured a cleat 24 for securing the free end 25' of the rope after putting on any desired tension by the user by forcibly pulling the same through the power multiplying pulley blocks 22 and 23. To provide the user with an 35 indication of the tension being applied to his leg a spring scale 26 is interposed in the length of rope 16 so that the user can easily read it as he pulls on rope 25. Thus the user may put any desired tension on his leg and secure the rope 40 by winding it back and forth on the cleat 23.

One or both of the side members 3 are extended past pivot 4 to serve as handles 27 whereby the user can work his leg up and down and exercise the knee joint while under tension. The 45 handle or handles may also be locked to the base board 2 as by one or more strap loops 28 or other suitable catches, so as to hold the leg straight out under tension for any desired length of time.

While the leg is held under tension the handles 50 12 may be adjusted to bring the pivotal axis of the swinging frame from a point coincident with the knee joint to a position above or below the same and to thereby force the knee in the oppo- 55

site direction respectively as a resultant of the tension.

To relieve the fatigue caused by the out-stretched foot I provide a wide canvas belt 29 5 or band passing under the shoe and secured at opposite ends to the side members 3 of the swinging frame.

The above apparatus works equally well on either leg and enables the user to thoroughly 10 exercise either knee with or without tension as may be desired, or may subject the leg to tension without exercising the same, or while under tension flex the knee back and forth by working the screws 11.

15 My use of the word "rope" in the appended claims is intended to cover any similar flexible device as a belt or chain.

Having thus described my invention, what I claim is:

20 1. In a knee exercising apparatus, a seat member on which a patient may sit with his knee joint at the forward edge of the seat, a guide bracket at each side of the forward end of the seat and extending upwardly therefrom, bearings 25 supported by said brackets for vertical sliding movement, means to adjust the vertical heights of said bearings to aline them with the pivotal

axis of the knee joint, and a swinging lower leg supporting frame pivoted to said bearings and extending downwardly and forwardly from said pivots.

2. In a knee exercising apparatus, a seat member on which a patient may sit with his knee joint at the front edge of the seat, a supporting frame for the lower leg of the patient, means to secure the patient against forward movement on the seat, means to apply traction to the lower 10 leg during swinging of said supporting frame, and manually operative means to swing said frame.

3. In a knee exercising apparatus, a seat member on which a patient may sit with his knee joint at the forward edge of the seat; a guide bracket at each side of the forward end of the seat and extending upwardly therefrom, bearings supported by said brackets for vertical sliding movement, means to adjust the vertical heights 20 of said bearings to aline them with the pivotal axis of the knee joint, means to secure the patient against forward movement on the seat, means to apply traction to the lower leg during swinging of said supporting frame, and manually operative means to swing said frame.

HARRY J. CAMPBELL.
